UNITED STATES PATENT OFFICE

GEORGE KOLLSTEDE, OF PROVIDENCE, RHODE ISLAND

DESIGN FOR A LIGHTER

Application filed October 29, 1928. Serial No. 28,684. Term of patent 14 years.

To all whom it may concern:

Be it known that GEORGE KOLLSTEDE, a citizen in the United States, residing at Providence, of the county of Providence and State of Rhode Island, has invented a certain new, original, and ornamental Design for a Lighter, of which the following is a specification, reference being had to the accompanying drawings forming a part thereof.

Fig. 1 is a side elevation of a pocket lighter showing my new design, and

Fig. 2 is an end elevation thereof.

I claim:

The ornamental design for a lighter substantially as shown.

In testimony whereof I affix my signature.

GEORGE KOLLSTEDE.
